Patented Aug. 13, 1968

211,970

COMBINED STORAGE COMPARTMENT, FREEZER
CHEST, AND BAKING OVEN FOR USE IN PROC-
ESSING COMESTIBLES, SUCH AS PRETZELS,
PIZZA PIES AND THE LIKE

Walter R. Reach, 588 Washington Terrace,
Audubon, N.J. 08106

Filed May 19, 1967, Ser. No. 7,195

Term of patent 7 years

(Cl. D67—3)

Fig. 1

Fig. 2

Fig. 3Fig. 4

FIG. 1 is a side elevation of a combined storage compartment, freezer chest, and baking oven embodying my new design, as viewed from the left side,

FIG. 2 is a perspective view thereof as viewed from the front, left corner,

FIG. 3 is a side elevation thereof as viewed from the right side thereof, and

FIG. 4 is a perspective view thereof as seen from the front, right corner thereof.

The rear wall of the combined storage compartment, freezer chest, and baking oven is rectangular in form, flat and plain.

I claim:

The ornamental design for a combined storage compartment, freezer chest, and baking oven for use in processing comestibles, such as pretzels, pizza pie, and the like, as shown and described.
